UNITED STATES PATENT OFFICE.

EDGAR M. CORBETT, OF PATERSON, NEW JERSEY.

DESIGN FOR RIBBON.

No. 38,913.

Specification for Design.

Patented Nov. 26, 1907.

Application filed October 18, 1907. Serial No. 398,132. Term of patent 7 years.

To all whom it may concern:

Be it known that I, EDGAR M. CORBETT, a citizen of the United States, and a resident of Paterson, in the county of Passaic and State of New Jersey, have invented a new, original, and ornamental Design for Ribbons, of which the following is a specification, reference being had to the accompanying drawing, forming part thereof.

The figure is a plan view of a section of ribbon showing my new design.

I claim:

The ornamental design for ribbon, as shown.

EDGAR M. CORBETT.
